CLAIM

The ornamental design for a vein locator, as shown and described.

DESCRIPTION

FIG. 1 is a front perspective view of an embodiment of a vein locator according to our new design;

FIG. 2 is a top plan view of the vein locator shown in FIG. 1;

FIG. 3 is a bottom plan view of the vein locator shown in FIG. 1;

FIG. 4 is a right side elevational view of the vein locator shown in FIG. 1, the left side being a mirror image;

FIG. 5 is a front elevational view of the vein locator shown in FIG. 1; and,

FIG. 6 is a rear elevational view of the vein locator shown in FIG. 1.

The portions drawn in broken lines are shown for illustrative purposes only and form no part of the claimed design.
